FIG. - 4

UNITED STATES PATENT OFFICE.

JULIUS H. HILDEBRANDT, OF CLEVELAND, OHIO.

OIL BURNER.

Application filed August 17, 1925. Serial No. 50,595.

In the operation of oil burners, particularly those wherein the oil is fed by gravity and the air for supporting combustion is supplied under pressure, it is very difficult 5 to maintain an oil operated pilot light after the burner has heated a room to the desired degree of heat and the automatic control apparatus has functioned to shut off the main supply of oil. The chief objection to 10 the use of an oil pilot, when the main blower is shut off, is the presence of incomplete products of combustion due to the lack of sufficient air. On the other hand, if the 15 main blower is allowed to function while the main oil supply is shut off, then more oil than is necessary, must be used to keep the flame from being blown out. Moreover, to 20 permit constant operation of the main blower involves an element of expense, which is detrimental to the satisfactory operation of an oil burner.

The principal object of the present invention is the provision of means for enabling an oil pilot light to be maintained 25 in operation after the main oil supply has been shut off and to keep such pilot light burning satisfactorily without necessitating the operation of the main blower.

I accomplish the above objects by employing a main blower and an auxiliary or 30 pilot blower with suitable electrical connections for shutting off one when the other is in operation. Moreover, I employ a burner wherein the main supply of air for 35 supporting combustion, as well as that which is used in connection with the operation of the pilot, is caused to flow through the same burner conduit whereby the surface across which the oil is flowing can be maintained 40 clean and free from obstruction at all times.

Referring now to the drawings, Fig. 1 shows diagrammatically a furnace having an oil burner which is equipped with apparatus made in accordance with my invention; Fig. 45 2 is a plan view of the burner and operating mechanism apart from the furnace; Fig. 3 is a plan view partly in section, of the main and pilot air conduits showing the junction therebetween; Fig. 4 is a vertical 50 section through the oil distributor; and Fig. 5 is a schematic wiring diagram showing

the electrical connections which may be employed for operating the blower motors.

Referring now to Fig. 1, 10 indicates a furnace having a grate 11 and an ashpit door 55 opening 12 which are made in the usual way. Supported upon the grate I have shown a burner 13 which may be any form of burner, but as illustrated, is one which is shown and described in Patent No. 1,570,448 issued to 60 me January 19, 1926. Oil may be supplied to the burner from tank 15 through main pipe 16. An adjustable valve 17 may control the quantity of oil which is flowing to the burner while the second valve 18 in 65 the by-pass 19 may control the quantity of oil which is allowed to flow into the burner when the pilot light is in operation. An automatically controlled stop valve 20 functions to stop and start the main oil supply 70 in accordance with temperature requirements, while the valve 18 after being once adjusted to the desired amount, remains undisturbed independently of whether or not oil is flowing through the valve 20. 75

The by-pass 19 as well as the main supply line 16 leads into a fuel supply conduit 21 which is shown in Fig. 4 as being connected to a distributor 22. From the distributor oil may flow down spaced passage- 80 way 23, then through passageway 24, and fall upon the baffle 25 shown in Fig. 1. Accordingly the same passageways are used for the flow of oil during the operation of the main oil supply and of the pilot oil 85 supply.

The air for supporting combustion may be supplied by a main blower 30 and by an auxiliary or pilot blower 21. The motors for operating these blowers are indicated at 90 32 and 33 respectively. The blowers may be mounted on a base 34 outside the furnace and in front of the ashpit door opening. An air pipe 35 leading from the main blower is shown as extending into the ashpit, and 95 then upwardly through the grate communicating with conduit 36 which surrounds the oil pipe 21.

The air from the pilot blower may flow 100 through air pipe 37 which merges with the pipe 35 preferably at a point outside the furnace. At the junction of the two air

pipes, I have shown a valve 38 which may be moved by pneumatic pressure to entirely close the opening in the pipe 37 when the main blower is in operation. The use of 5 such valve prevents the escape of air rearwardly through the pipe 37 when the main blower is in operation. On the other hand the diminutive size of the pilot blower is such that the pressure created thereby is not 10 sufficient to necessitate an entire closing of the pipe 35 through the blower 30 when the pilot blower only is in operation. Consequently I have shown the valve 38 as being sufficient in size only to close the opening 15 across the pipe 37, but not sufficient to close the opening in the pipe 35 when in the position indicated by the broken lines 38^a in Fig. 3.

The control mechanism which I employ 20 is such that the main blower is in operation when the pilot blower is stopped and that the pilot blower is in operation when the main blower is stopped. Moreover, the control mechanism is such that the pilot oil 25 supply is always on, while the main oil supply is turned on or off in accordance with the temperature requirements. To accomplish this, I have shown a thermostat which may be indicated in general at 40 and which 30 may be electrically connected to a control mechanism 41 which functions to operate a switch 62 when the temperature reaches a predetermined degree. In Fig. 5, the switch is shown as comprising a single pole, double 35 throw switch with connections so made that the main motor 32 is on when the pilot motor 33 is off. For example in Fig. 5 the full line position of the switch 42 enables current to flow from the source of supply 45 through line 46, switch arm 47, contacts 48, line 49, motor 32, line 50 and back to the source of supply. When the switch is in the position shown by the dotted lines 42^a, then current flows through line 46, switch 40 arm 51, contact 52, line 53, pilot motor 33, line 54, line 50 and back to the source of supply.

While the main blower is in operation, 50 the valve 20 is maintained in open position by means of a mechanical connection between the valve and the switch 42. This connection is shown as a chain 55, one end of which is connected to arm 56 on the switch shaft 57, and the other end of which 55 is connected to a lever 58 which operates the valve 20. When the position of the switch is changed to energize the pilot motor, then the valve 20 is moved to closed position by means of a weight 59, shown in Fig. 1. 60 In this way, the main oil supply is shut off when the main blower is stopped but is turned on when the main blower is placed in operation. In the meantime, the oil pilot 65 valve remains open for supplying oil to the pilot light so that there is a constant

flow of oil through the oil pipe 21 and into the oil distributor. This enables the passageways to be kept clean, since it avoids the opportunity for gummy deposits to collect, due to suspension of the oil movement. 70 Thus, the air supply is diminished when the oil supply is diminished and as a result I obtain a burner which may be economically operated, yet which may supply sufficient quantities of air and oil to insure efficient 75 operation at all times.

A burner made in accordance with my invention may be satisfactorily operated without any moving parts within the furnace and without any complicated mechanism outside 80 the furnace. The chief objection, namely, the presence of incomplete products of combustion in the furnace chamber has been entirely overcome, and the operation costs have been reduced to a minimum. The use 85 of the pilot blower has permitted the utilization of an adequate oil pilot flame and has obviated the necessity for a gas pilot. I thus produce an extremely simple burner 90 which enables the air to be controlled independently of the oil and thereby permits efficient operation under different conditions. 95

I claim:

1. In an oil burner the combination with 100 an air conduit, of a main air supply blower and a pilot air supply blower, an air pipe leading from one of said blowers to the conduit, a second air pipe leading from the other blower and connected to the first mentioned pipe, and a valve adjacent the connection of 105 said pipes, said valve functioning to be moved by pneumatic pressure to close the opening leading to one of the pipes when one of the blowers is in operation.

2. In combination an oil burner adapted 110 to be mounted within a furnace, an oil supply conduit leading upwardly through the center of the burner, an oil distributor carried by the burner and operatively connected to the oil pipe, an air conduit surrounding the oil supply pipe and terminating at one end adjacent the distributor, the other end of the conduit leading outwardly from the furnace, a main blower having 115 an outlet conduit connected to the air conduit, and a pilot air blower having an outlet conduit connected to said air conduit, a valve adjacent the connection of the pilot blower conduit with the air supply conduit, said valve functioning to close the pilot blower conduit when the main blower is in operation, a main oil supply valve, and a pilot oil supply valve, means for closing the main oil supply valve, when the main blower is 120 stopped and for simultaneously starting the pilot blower, said pilot oil supply valve being open independently of the position of the main oil supply valve.

3. In combination, an oil burner having 125 an oil distributor, a main oil supply con-

duit and a pilot oil supply conduit having a common outlet in said distributor, a main and a pilot air supply, a common air conduit leading from the main and pilot air supplies and terminating adjacent said distributor and a valve associated with said air supply conduit for automatically cutting off the passage of air from one source of

air supply when the other is in operation, and means for automatically stopping the main oil supply when the main air supply is off. 10

In testimony whereof, I hereunto affix my signature.

JULIUS H HILDEBRANDT.
